UNITED STATES PATENT OFFICE

HENRY C. WESTPHAL, OF EL PASO, TEXAS

PUNCTURE MARKER AND TUBE DEFLATER

Application filed May 29, 1931. Serial No. 540,973.

This invention relates to a device for marking punctures in tubes and for deflating the tubes, the general object of the invention being to provide a device which is adapted to be inserted in a puncture when a tube is inflated and put in water in order to find out where the punctures are, whereby all the punctures in the tube can be marked by inserting one of these devices in each puncture and then by removing a cap from one of the devices, the tube will be rapidly deflated by the air exhausting through said device.

This invention also consists in certain other features of construction and in the combination and arrangement of the several parts, to be hereinafter fully described, illustrated in the accompanying drawings, and specifically pointed out in the appended claim.

In describing the invention in detail, reference will be had to the accompanying drawings wherein like characters denote like or corresponding parts throughout the several views, and in which:

Figure 1 is a view of an inflated tube showing two of the devices used to mark two punctures therein.

Fig. 2 is a section on the line 2—2 of Fig. 1.

Fig. 3 is a top plan view with the cap removed.

Fig. 4 is a view partly in section showing a modification.

In these drawings, the numeral 1 indicates the body of the device which is formed with a threaded reduced top part 2 for receiving a cap 3 of the type used on valve stems. The body is of substantially conical shape with a point 4 at its small end. This point is enlarged at its center and gradually decreasing in thickness to each end as clearly shown in Fig. 2 so that when the point is pushed into a puncture, there is no danger of the device being forced out of the puncture by the air pressure in the tube. A bore 5 passes through the body, the upper part 2, and the point 4 and the upper end of the bore is normally closed by the cap 3.

The modification shown in Fig. 4 has the body 1' tapering from its upper end to the point with the point slightly enlarged as shown at 4' and in this form of the device,

the point is provided with the lateral holes 6 which communicates with the bore, so that when the cap is removed, the air in the tube will rapidly escape through the device.

The device is knurled as shown at 6 to prevent it from slipping in the hands when the same are wet.

The tube to be repaired is inflated and put in water in the usual way in order to ascertain where the punctures are located. When a leak is found one of the markers is inserted in the puncture and then the tube is further inspected for any other punctures and if these are found, a device is inserted in each one of them. When all the punctures have been found, and marked, the tube is removed from the water and the cap from one of the devices is removed so that the air in the tube will escape and then the tube can be repaired in the usual manner, the marker remaining in place until the puncture in which it is placed is to be repaired.

The modified form of the device shown in Fig. 4 is used for small punctures.

It is thought from the foregoing description that the advantages and novel features of the invention will be readily apparent.

It is to be understood that changes may be made in the construction and in the combination and arrangement of the several parts, provided that such changes fall within the scope of the appended claim.

Having thus described my invention what I claim as new is:

A puncture marker and tube deflater comprising a body having a point at one end thereof and a threaded nipple at the other end thereof, the point having an enlarged intermediate portion whereby the same will be held in the puncture, said body having an unobstructed bore passing through the point and the body and the threaded nipple, and a cap threaded on the nipple for closing the outer end of the bore.

In testimony whereof I affix my signature.

HENRY C. WESTPHAL.
